(57) CLAIM

The ornamental design for a Buddha planter, substantially as shown and described.

DESCRIPTION

FIG. 1 is a front, side perspective view of a Buddha planter, according to my new design;

FIG. 2 is a front elevation view thereof;

FIG. 3 is a top, front perspective view thereof;

FIG. 4 is a bottom plan view thereof; and,

FIG. 5 is a front elevation view thereof, including broken lines which show plants and which form no part of the claimed design.

1 Claim, 5 Drawing Sheets

FIG. 1

FIG. 2

FIG. 3

FIG. 4

FIG. 5
